UNITED STATES PATENT OFFICE.

ANCHEL COHEN, OF PITTSBURGH, PENNSYLVANIA.

FIRE ESCAPE.

Application filed July 26, 1923. Serial No. 653,877.

To all whom it may concern:

Be it known that I, ANCHEL COHEN, a citizen of the United States, residing at Pittsburgh, in the county of Allegheny and 5 State of Pennsylvania, have invented certain new and useful Improvements in Fire Escapes, of which the following is a specification.

This invention relates to certain new and 10 useful improvements in fire escapes, and important objects thereof are to provide a device for facilitating escape from a burning building; which embodies novel means for completely collapsing and storing the 15 ladder member when not in use; which includes a spring operated spool element adapted to facilitate the positioning of the ladder for use, and which may be readily secured to the outer face of the wall of a 20 building.

Further objects of the invention are to provide a device of the character described, in a manner as hereinafter set forth, which is simple in its construction and arrangement, 25 strong, durable and efficient in its use, and comparatively inexpensive to manufacture.

To the accomplishment of these and such other objects as may hereinafter appear, the 30 invention consists of the novel construction, combination and arrangement of parts herein specifically described and illustrated in the accompanying drawing wherein is shown an embodiment of the invention, but it is to be understood that changes, variations 35 and modifications may be resorted to which come within the scope of the claim hereunto appended.

In the drawing forming a portion of this 40 specification and wherein like numerals of reference designate corresponding parts throughout the several views:

Figure 1 is a fragmentary front elevation of 45 a fire escape in the operative position in accordance with my invention with portions thereof shown in cross section.

Figure 2 is a sectional side view of a wall 50 structure provided with a window, showing an embodiment of my invention attached to the outer face thereof beneath the window.

Figure 3 is a sectional view of a ladder rung and associated parts.

Figure 4 is an end view of the ladder spool illustrating the spring casing and the 55 actuating spring carried thereby, with the outer wall of the spring casing removed.

Figure 5 is an enlarged detail view of the latching key and latch.

Referring in detail to the drawing 1 denotes a wall structure of a building including 60 a window 2. A receptacle 3, consisting of a rear wall 4, bottom 5, front wall 6, end walls 7 and 8, and a cover 9, is fixed to the outer face of the wall structure 1 directly beneath the window 2, by means of securing 65 bolts 10, which latter engage the rear receptacle wall 4 and the wall structure 1.

The receptacle 3 is preferably rectangular in contour and is constructed from sheet metal. The end walls 7 and 8 thereof are 70 fixedly secured to respective ends of the rear wall 4. The rear end of the bottom 5 is hinged, as at 11, to the lower end of the rear wall 4, and the front end of the bottom 5, is hinged, as at 12, to the lower end of 75 the front wall 6, while the upper end of the latter is hinged, as at 13, to the rear end of the cover 9.

The rear end of the cover 9 carries a pivotally mounted centrally disposed catch 14 80 adapted to engage in an opening provided therefor in the rear wall 4 for securing the receptacle in the closed position, as shown in Figure 2, of the drawing.

The cover 9, front wall 6, and bottom 5 85 are not connected with the end walls 7 and 8, of the receptacle 3, and when the catch 14 is released from its engagement with the rear wall 4, the cover 9, front wall 6, and bottom 5, due to their respective hinged connections 13, 12 and 11 will drop by gravity to the vertical position in alignment with respect to each other and with the vertically disposed rear wall 4, as is clearly shown in Figure 2, of the drawing, and for 95 the purpose to be described.

An axle 15 is horizontally disposed in the receptacle 3 and is provided with squared ends which engage in the supporting hubs 16 fixed to the inner face of respective end walls 7 and 8, and prevent the rotation of the axle 15 for the purpose to be described.

A spool 17, on which the ladder 18 is adapted to be wound when not in use, is rotatably mounted on the axle 15. One end 105 of the spool 17 is provided with an ordinary spool flange 17' and a ratchet wheel 19 is fixed to the outer face of the latter to rotate therewith. The other end of the spool 17 is provided with a spring casing 20, the inner wall 21 of which serves for the purpose of the ordinary spool flange.

A coil spring 22 is mounted in the spring casing 20 and has its inner end fixedly attached to the axle 15, as indicated at 23. The outer end of the coil spring 22 is free 5 and is formed to provide a hook 24.

The inner casing wall 21 is formed with an elongated rectangular slot 25 disposed tangentially and adjacent to the periphery of the inner casing wall 21. A correspondingly shaped latch 26 is pivotally connected at its approximate center in the slot 25, as indicated at 27. The pivotal connection 27 of the latch 26 in the slot 25 is frictional and the latch 26 is shiftable to position the latter either in longitudinal alignment in the slot 25 or at right angles relatively thereto. When in the latter position the latch 26 will be disposed parallel with respect to the spool 17 with a portion extending outwardly into 20 the spring casing 20 and with a portion projecting inwardly over the spool 17, as clearly shown in Figure 1, of the drawing, and for the purpose hereinafter described.

The ladder 18 consists of two parallelly 25 extending chains 28, provided at regularly spaced intervals with rungs 29. Each of the rungs 29 consists of a rod 30 the ends of which extend and project through corresponding links of respective chains 28. A 30 pipe 31 is mounted on the rod 30 intermediate of the chains 28 for the purpose of keeping the chains 28 properly spaced from each other. Each end of the rod 30 is provided with a short pipe 32 and is riveted for securing the latter in position. The outer end of each of the pipes 32 is threaded and is provided with a cap 33. The rod projections with respective pipes 32 and caps 33 provide hand holds to facilitate the scaling 35 of the ladder. In addition, the construction prevents the lateral outward movement of the chains 28 on the rungs 29.

The rungs 29 of the ladder 18 are of a length to allow them to be wound, together 40 with the chains 28, on the spool 17 between the flange 17' and the inner wall of the spring casing wall 21.

Each of the ladder chains 28 has one end thereof fixed to the spool 17, as indicated 45 at 34.

A ratchet lever 35 is pivotally connected to the inner face of the front wall 6 of the receptacle 3, and engages the ratchet wheel 19 for securing the spool 17 in the tensioned 50 position when the receptacle is in the closed position, as shown in dotted lines in Figure 2, of the drawing.

A loose segmental latch key 36 made from strip metal and formed with an offset 37 is 55 provided for locking the latch 26 in the operative position when the ladder 18 is wound upon the spool 17 in the manner now to be described.

When winding the ladder 18 upon the 60 spool 17 the latter is rotated manually in

any manner in the counter clock-wise direction. Until the greater portion of the ladder 18 has been wound upon the spool 17 the latch 26 is longitudinally positioned and maintained in its slot 25 and will be flush 70 with the faces of the inner casing wall 21 in which it is pivoted. When the roll, formed by winding the ladder 18 upon the spool 17, reaches the slot 25 in the inner casing wall 21, the latch 26 is manually shifted 75 to position it at right angles with respect to the slot 25 in the inner casing wall 21, as shown in Figure 1, of the drawing. The portion of the latch 26 extending into the casing is engaged by the hook 24 on the free 80 end of the spring 22, and the latch key 36 is loosely placed to extend circumferentially on the partially wound ladder roll on the spool 17. The key offset 37 is positioned to 85 abut against the inwardly projecting portion of the latch 26 to maintain the latter in engagement with the spring 22. The key 36 is held in position upon the ladder roll by subsequent turns that are added after the key 36 has been placed in position to secure 90 the latch 26.

Upon again continuing the rotation of the spool 17 to completely wind thereon the unwound portion of the ladder 18, after the hook 24 of the spring 22 has engaged the latch 26 as above described, the spring 22 will be tensioned and held in such tensioned position by positioning the bottom 5, front wall 6 and cover 9 of the receptacle in the closed position for when in such position the ratchet lever 35 may be shifted to engage one of the teeth of the ratchet wheel 19 to maintain the spool 17 in the tensioned position. By engaging the catch 14 of the cover 9 with the rear receptacle wall 4 the receptacle 3 100 will be maintained in the closed position with the spring 22 properly tensioned, to initially actuate the spool 17 when the use of the device is required.

When it is desired to lower the ladder 18 for use, the catch 14 is released, allowing the cover 9, front wall 6, and bottom 5, to drop by gravity to the vertical position shown in Figure 2 of the drawing. The spool 17 being tensioned for rotation in the clockwise direction by the action of the spring 22, the ratchet wheel 19, carried by the spool 17, will tend to force the front receptacle wall 6 outwardly by its engagement with the latter through the ratchet lever 35 thereby accelerating the positioning of the hinged bottom 5, front wall 6 and cover 9 to the vertical position as above described.

When the ratchet lever 35 disengages the ratchet wheel 19, the spool 17, on which the ladder 18 is wound, will rotate in the clockwise direction by the action of the spring 22, and the ladder 18 will unwind from the spool 17 to the lowered or extended position. As the latch key 36 is held in posi- 125

tion by its engagement with certain coils of the ladder 18, the former will be released to drop free as soon as such securing coils are unwound from the spool 17 by the action of spring 22. Upon release of the latch key 36 the latch 26 will shift into the slot 25 due to the pull thereon of the spring 22, and thereby disengage the spring hook 24 from the latch 26. The spring 22 is now disconnected from the spool 17 and will remain idly distensioned on the axle 15. The spool 17, however, will continue its rotation to lower the ladder 18 as a sufficient portion of the latter will have been fed out to supply ample weight to provide for the continuation of the unwinding operation by the descent of the ladder to the lowered position.

It will be noted that in positioning the ladder 18 for use it is only necessary for the operator to release the cover catch 14 from its engagement with the rear wall 4 of the receptacle 3.

What I claim is:—

In combination a fire escape comprising a receptacle adapted to be secured to the outer face of a wall structure beneath a window opening, said receptacle having its rear wall, bottom, front wall, and cover hingedly connected together to permit of said bottom, front wall, and cover shifting by gravity to a vertical position in alignment with said rear wall, said cover provided with a catch

adapted to engage said rear wall for securing said receptacle in the closed position, a horizontally disposed axle fixedly carried by the end walls of said receptacle, a spool rotatably mounted on said axle, said spool having one end provided with a flange supporting a ratchet wheel and the other end thereof provided with a spring casing, the inner wall of said casing formed with a slot, a latch member pivoted in said slot, a flexible ladder having one end secured to said spool and adapted to be wound thereon, a latch key adapted to be secured by its engagement by said ladder for securing said latch member at right angles with respect to said inner wall, a spring mounted in said casing and having one end fixed to said axle and the other end thereof formed to provide a hook capable of engaging said latch member when the latter is positioned at right angles with respect to said inner wall, for tensioning said spring when said spool is rotated to wind said ladder thereon, and a ratchet lever carried by said front receptacle wall and engaging said ratchet wheel for securing said spool in the tensioned position when said receptacle is in the closed position, substantially as described and for the purpose set forth.

In testimony whereof I affix my signature.

ANCHEL COHEN.
